UNITED STATES PATENT OFFICE.

FRANK B. METZGER, OF BAYONNE, NEW JERSEY.

AMUSEMENT DEVICE.

SPECIFICATION forming part of Letters Patent No. 783,214, dated February 21, 1905.

Application filed September 12, 1903. Serial No. 172,864.

To all whom it may concern:

Be it known that I, FRANK B. METZGER, a citizen of the United States, residing at Bayonne, in the county of Hudson and State of New Jersey, have invented certain new and useful Improvements in Amusement Devices, of which the following is a specification, such as will enable those skilled in the art to which it appertains to make and use the same.

10 This invention relates to amusement devices of the class known as "shadowgraphs," by which the image of animals may be cast on a wall, screen, or other receiver by means of the aid of an artificial light; and the object 15 thereof is to provide an improved device of this class which is simple in construction and operation and comparatively inexpensive and which is designed to amuse both old and young.

The invention is fully disclosed in the following specification, of which the accompanying drawings form a part, in which the separate parts of my improvement are designated by suitable reference characters in each of the views, in which—

25 Figure 1 is a view of one side of my improved shadowgraph and showing the method of operating the same; Fig. 2, a view of one side of a detail thereof, and Fig. 3 a view of the reverse side of the shadowgraph shown 30 in Fig. 1.

In the practice of my invention I provide a plate or board a , which is composed of cardboard or any other suitable thin material and provided with a central opening a^2 , which is 35 preferably circular in form and into which from one side thereof projects a radially-arranged member b , the front side of which is printed or painted to represent the human hands, said hands and the fingers and thumbs 40 thereof being in the position to form the shadow or representation of the head of a hound, in which position the thumbs b^2 represent the ears, the central part b^3 of one hand the head of the hound, and the third and 45 fourth fingers b^4 and b^5 the upper jaw, which is designated as a whole by the reference character b^6 .

Pivoted to the back of the plate or board a at c is an elbow-shaped member d , provided 50 with an arm d^2 and a shank d^3 , which shank

passes through a slot e in the plate or board a and is provided with a thumb or finger piece d^4 , while the arm d projects forwardly and is provided with two fingers d^5 and d^6 . A keeper f is also preferably secured to the back of the 55 plate or board or to the head member b thereof, through which the arm d^2 passes, and in the position of the parts shown in Fig. 1 the finger d^5 forms the lower jaw of the head of the hound and the finger d^6 is concealed; but 60 in the position of the parts shown in Fig. 3 the finger d^6 forms the tongue of the hound.

In Fig. 1 of the drawings I have shown at g an artificial light and have indicated at h a wall, screen, or other receiver on which an 65 image may be thrown, and in practice the plate or board a is held, as shown in Fig. 1, between the light and the wall or screen, and in the position of the parts shown in Fig. 1 the image of the head of the hound will be 70 thrown on the wall or screen, as shown by the shade or shaded lines i , and in order to show the mouth of the hound open and the tongue the thumb or finger is placed on the piece d^4 of the movable member d and the 75 fingers d^5 and d^6 are depressed, as indicated in full lines in Fig. 3 and in dotted lines in Fig. 1. Any other animal or the image thereof may be produced in the same manner, all that is necessary being to change the form of 80 the part b and the movable part d . If it is desired to illustrate or produce the image of an elephant or an elephant's head, the main part b within the opening a^2 will be so formed as to represent the head of an elephant, while 85 the movable part d will be formed to represent the trunk. If it is desired to represent or form the image of the head of a mule, corresponding changes will be made in the part b , while the part d will be formed to represent the 90 ears, and in this manner the image or representation of any desired animal may be cast upon a wall, screen, or other receiver in the manner herein described.

In practice the front side of the plate or 95 board a is preferably provided with pictures of various animals, as shown in Fig. 1; but this is immaterial and forms no part of the invention.

Having fully described my invention, what 100

I claim as new, and desire to secure by Letters Patent, is--

A device of the class described, comprising a plate or board having a large central opening and with one side of which is connected a stationary member which projects into said opening and is shaped to represent part of an animal, and a movable member pivoted to the back of said plate or board and representing another part of said animal and also projecting into said opening, said plate or board being provided with a slot and said movable

member with a thumb and finger piece which projects therethrough, and whereby said movable member may be operated, substantially as shown and described. 15

In testimony that I claim the foregoing as my invention I have signed my name, in presence of the subscribing witnesses, this 11th day of September, 1903.

FRANK B. METZGER.
